UNITED STATES PATENT OFFICE.

FRANK PHELPS, OF WELLSTON, OKLAHOMA, ASSIGNOR TO THOMAS GIN COMPRESS COMPANY, OF LITTLE ROCK, ARKANSAS, A CORPORATION OF NEW JERSEY.

COTTON-GIN.

1,022,259.

Specification of Letters Patent.

Patented Apr. 2, 1912.

Application filed January 25, 1907. Serial No. 354,077.

To all whom it may concern:

Be it known that I, FRANK PHELPS, a citizen of the United States, residing at Wellston, in the county of Lincoln, State of Oklahoma, have invented certain new and useful Improvements in Cotton-Gins; and I do hereby declare the following to be a full, clear, and exact description of the invention, such as will enable others skilled in the art to which it appertains to make and use the same.

The main object of my invention is to provide for effectively removing the lint from the saws of a cotton-gin by means of an air-blast acting on the perimeters of the saws, in conjunction with provision for causing the cleaning of the fiber and ejection of all dust, motes, dirt and waste from the lint after leaving the roll-box and before reaching the air-blast.

My invention is preferably incorporated in a cotton-gin of the character set forth in my prior U. S. Patent No. 809131, dated January 2, 1906, and may be considered an improvement thereof. In said patented machine, the trash, motes, etc., are ejected by centrifugal action from exposed portions of the saws in an open space or chamber directly back of the saws, and fall or settle by gravity into a trough or receptacle at the bottom of such space or chamber, whence they are carried off by a suitable conveyer.

Without essentially restricting my improvement to the specific constructions illustrated, the invention will hereinafter be fully described by reference to the accompanying drawings, which form a part of this specification, and then more particularly pointed out in the claims following this description.

In said drawings, Figure 1 is a sectional perspective view of a cotton-gin embodying my invention. Fig. 2 is a detail view. Fig. 3 is a cross-section of a gin having my invention embodied therein in another form. Fig. 4 is a view similar to Fig. 3, showing still another form or embodiment of the invention.

In the several figures, the same general construction of gin is represented, the ginning mechanism and waste-ejecting means being substantially similar to that set forth and described in the specification of my aforesaid patent.

The letter A indicates the roll-box, in

which the untreated cotton is engaged by the revolving saws B, the latter drawing the cotton through or between the bars of the breast-plate or grating C, thereby separating the cotton in the usual way, the seeds being retained in the roll-box and suitably disposed of, while the cotton fiber or lint adheres to the saw-teeth. Back of the breast-plate, the saws are exposed in an open space or chamber D, wherein the dust, motes and waste are ejected from the lint on the saws by centrifugal action, and fall or settle by gravity into a longitudinal trough or channel E having a conveyer F therein for carrying off the trash. Said trough E, constituting the bottom of the settling-chamber D, is formed behind an upright longitudinal divider-board G, adjacent to the perimeters of the saws approximately back of the axis of rotation thereof. As explained in the specification of my aforesaid patent, the divider-board G has a curved or concave front face approximately conforming to and disposed close to the peripheries of the saws; while the opposite or rear surface of the divider-board slants downwardly from a sharp edge at the top and into the aforesaid channel or trough E, thus facilitating the collection and settling of trash, motes, etc., by causing every particle thrown from the saws to slide down the back of the divider-board to the conveyer.

For removing the lint from the saws, a lint-chute H has its mouth J arranged to inclose the lower back portions of the saws, just below the divider-board G; and an air-blast coming from a tube or casing K, having a contracted chute L adapted to discharge at or into the mouth of said lint-chute, strikes approximately tangentially the peripheral portions of the saws exposed in the mouth J of the lint-chute, thereby blowing off the lint from the saw-teeth, which latter point in the same direction as the motion of the air-blast. The air-tube K may be in communication with any suitable form of pneumatic blower or fan, as indicated at M, to create the necessary blast. The lint-chute H may discharge on to a conveyer, or into any suitable receptacle, the air-currents created by the aforesaid air-blast blowing off the lint through said chute, or the said chute may communicate with a suction-tube, as well understood. In Fig. 3 H¹ indicates such a suction tube and H² the

fan or other device for inducing the current.

In Fig. 1, the divider-board G and conveyer-trough or channel E are shown constructed integrally with and as a part of the air-tube K, which latter may be of sheet-metal, bent to provide the aforesaid divider-board and channel, while the lower side of said tube is carried up into the space between the front and rear walls of the divider-board, thus providing a narrow or contracted inverted U-shaped mouth for the discharge of the air-blast onto the peripheries of the saws. The lint-chute H may also be of sheet-metal.

In Figs. 3 and 4, the conveyer-channel or trough E is shown formed in a wooden block, the front side of said channel constituting the divider-board G, as shown in the drawings of my aforesaid patent. In these cases, the discharge-chute L of the air-tube K passes under the divider-board. In Fig. 4 the air-tube K is located back of the conveyer, and has a narrow or contracted discharge-chute passing thereunder and communicating with the upper side of the mouth J of the lint-chute. In Fig. 3, the air-tube K is arranged below the conveyer-trough E. In this case, the tube E comprises a cylinder rolled in the form of an involute curve, leaving a narrow or contracted discharge passage into the mouth of the lint-chute just below the divider-board and conveyer.

In order to concentrate the air-blast on the saw-teeth, and prevent the air-blast from wasting or passing between the saws, a series of triangular or wedge-shaped partitions may be arranged in the discharge-passage L from the air-tube K, as indicated by the letter l in Fig. 2. Said Fig. 2 shows the partitions on an enlarged scale. They are small wedge-shaped pieces spaced apart at intervals corresponding to the spacing of the saws; the air passes through them in the direction indicated by the arrow, and the exit of the air is between the broader ends of the partitions, adjacent to the peripheries of the saws, thus concentrating the air-blast on the teeth.

It will be observed that the structure for providing the stripping blast, consisting of the air chamber and lint flue into which it discharges through the contracted blast-chute or nozzle, may be considered as constituting a conduit through the wall of which the saws project, said conduit being divided by a partition into two chambers, that is the air chamber K and lint chamber H, between which current is created so as to be directed against the perimeters of the saws transversely of the gin cylinder. It will also be observed that in Figs. 1 and 3 the portions of the saws from which the lint is stripped by the blast are arranged between the terminals of the upper wall of

the blast nozzle and end of the lower wall of the throat of the lint flue, and that the lower or outer wall of the blast nozzle is formed by the upper wall of the lint throat which provides a surface adjacent to and confronting the saws which the blast follows and thus effectively strips the lint.

I claim as my invention and desire to secure by Letters Patent:

1. A cotton gin, including a conduit, through the walls of which the saws are arranged to project, a partition dividing the conduit in two chambers, and means for creating an air current between the chambers to be directed against and transverse 80 the saws.

2. A cotton gin, including a conduit, through the walls of which the saws are arranged to project, a partition dividing the conduit in two chambers, said partition terminating adjacent one wall of the conduit to provide communication between the chambers, means for creating an air blast in one chamber, and means for creating an air suction in the other chamber.

3. In a gin, the combination with the saws, of a lint-chute or receptacle having its mouth adjacent to and substantially inclosing peripheral portions of the saws, and an air-tube or chamber having a contracted 95 exit-chute delivering into said mouth and arranged to direct an air-blast approximately tangentially on the peripheries of the saws, and a series of wedge-shaped partitions arranged in the exit-chute of the air-chamber near or adjacent to the mouth of the lint-receptacle and adapted to concentrate the air-blast upon the peripheries of the saws.

4. In a gin, the combination with the 105 saws, of a lint-chute or receptacle having its mouth adjacent to peripheral portions of the saws, and a sheet-metal air-tube having a contracted exit-chute extending from one side thereof and arranged to discharge into the mouth of said lint-chute and to direct an air-blast approximately tangentially on the peripheries of the saws, the upper surface of said exit-chute being formed to provide a longitudinal trash-receptacle and divider-board adjacent to the backs of the saws, and the lower surface thereof terminating in the space between the divider-board and trash-receptacle, leaving a narrow exit-passage for the air-blast.

5. In a gin, the combination with the saws, of means including an air chamber arranged behind the lower portions of the saws and having a generally involute form to provide a nozzle for applying a stripping blast to the under portions of the saws.

6. In a gin, the combination with the saws, of an air blast stripper including a blast nozzle and lint throat into which it delivers, the upper wall of the blast nozzle terminat-

ing adjacent to the saws, and the lower wall of the blast nozzle being constituted by the upper wall of the lint throat.

7. In a gin, the combination with the saws, 5 of an air blast stripper including a blast nozzle one wall of which terminates at the saws while the other wall continues in proximity to and confronting the saws, providing a surface for directing the stripping 10 blast.

8. In a gin, the combination with the saws, 15 of an air blast stripper including an air chamber having a blast nozzle arranged to direct the stripping blast approximately tangentially to the peripheries of the saws, one wall of the blast nozzle terminating ad-

jacent to the saws and the other continuing in proximity thereto.

9. In a gin, the combination with the saws, 20 of an air blast stripper including a blast nozzle and lint throat into which it delivers, the saws being inclosed between the ends of one wall of the nozzle and one wall of the lint throat, there being a common partition which provides the other wall of both the 25 nozzle and lint throat.

In testimony whereof I affix my signature, in presence of two witnesses.

FRANK PHELPS.
